UNITED STATES PATENT OFFICE

GEORGE SYDNEY WHITFIELD, OF INGRAVE, ENGLAND, ASSIGNOR TO ILFORD LIMITED,
OF ILFORD, ENGLAND, A BRITISH COMPANY

COLOR PHOTOGRAPHY

Application filed January 9, 1932, Serial No. 585,768, and in Great Britain December 16, 1930.

This invention is concerned with improvements in or relating to processes of color photography which involve the combination of three or more "part-images" of the subject 5 in the production of the finished picture.

The term "part-image" as used herein, signifies an image of the subject obtained by means of light corresponding to a portion only of the spectrum. Generally three part- 10 images are made of the subject, viz, a blue, a green and a red part-image.

The final photograph is prepared from these part-image-records in the form of negatives, by making a colored positive print from 15 each of them and combining these positives according to one or other of the known methods employing either the additive or subtractive principle of color synthesis.

It is clearly desirable to expose simultaneously the sensitive surfaces which are to record the part-images. It is also very desirable, in order to obtain geometrically similar images of identical size that the sensitive surfaces should be so placed as to occupy during 25 exposure similar positions with regard to the subject to be photographed.

The present invention is concerned with methods for the production of colored photographs of the type in which a single part- 30 image of the subject is recorded on one sensitive emulsion, and simultaneously two or more further part-images of the subject are recorded through a multi-color screen on a second sensitive emulsion.

The present invention provides for use in the production of colored photographs by methods of the above type, the combination of a transparent support, an emulsion layer 40 which is adapted to record light from one region of the spectrum and is associated with that surface of the support which will face the lens, a second emulsion layer which is adapted to record light from at least two other spectral regions and is associated with 45 the rear surface of the support, and sandwiched between the two emulsion layers and on the support a multi-color screen adapted to pass light corresponding to the spectral regions to be recorded by the rear emulsion 50 layer.

According to a feature of the invention the front emulsion, that is the one facing the lens, is adapted to record light corresponding to the blue region of the spectrum only, the rear emulsion is a panchromatic one so that light 55 from the green and red regions may be recorded thereon and the multi-color screen which is sandwiched between the two emulsion layers is a two-color screen comprising juxtaposed green and red elements. The 60 screen may be of either the linear, the mosaic or the random type, but the linear type is preferred.

When a single support is employed for the two emulsions the front emulsion layer may 65 be a stripping layer, which is removed from the support after development, in order to ensure that the two emulsion layers are submitted to identical development conditions, and thus to ensure that any shrinkage or 70 other distortion of the support due to the treatment in the developing baths will affect the two emulsion layers equally.

Owing, however, to the difficulty of manipulating the emulsion layer during the operation of transference to a fresh support it is preferred according to another feature of the invention to employ a composite support comprising two separable layers (with or without an interposed layer of adhesive), each 75 80 carrying one of the emulsions.

After development positives corresponding in number to the number of part-images recorded by the rear emulsion may be printed therefrom either through filters corresponding in color respectively to the colors of the elements constituting the screen or by other known methods of image separation. Thus in the case of a two-color red and green screen, two positives may be printed from the rear 85 emulsion, one through a red filter and the other through a green filter. A third positive is printed from the negative obtained on the front emulsion layer.

A practical embodiment of the invention 90 will now be described by way of example, reference being made to the accompanying drawing in which the single figure is a diagrammatic illustration of the film assembly and lens.

A thin celluloid support 10 is coated with a blue sensitive emulsion 11 and a further thin celluloid support 13 is provided with a two-color screen 14 consisting of minute juxtaposed red and green elements, on top of which screen is coated a panchromatic emulsion 15.

These two films are then mounted in a camera with the blue-sensitive emulsion 11 on the support 10 facing the lens 16, the other support 13 being arranged behind the first-mentioned film with the emulsion side 15 thereof away from the lens.

The films in this position are exposed to light in the camera, a correcting filter 18 being preferably associated with the lens to intercept ultraviolet radiation and equalize the effects of the color components on the emulsion and thus to enable equally exposed part-images to be obtained.

In this manner the blue part-image is recorded on the front film and the red and green part-images on the rear film. The two films are then developed, fixed, washed and dried, care being taken to ensure equal treatment of the films.

A positive is then printed from the blue part-image upon a suitably sensitized surface and two further positives are printed in a similar manner from the other film with its associated two-color screen through green and red filters respectively onto suitably sensitized surfaces.

These three positives may then be suitably dyed and superimposed in register to give the final picture or alternatively the final picture may be prepared by transferring dyes from these positive part-images on to a single surface by imbibition in known manner. Again separate copies of the red and green part negatives may be prepared for use in any other well-known manner.

It is to be understood that the method according to the invention may be arranged to give a four colored picture by substituting a three-color screen for the two-color screen referred to above.

I claim:—

1. For use in the production of colored photographs the combination of a transparent supporting means, an emulsion adapted to record light from the blue region of the spectrum carried on that surface of the supporting means which will face the lens, a multi-color screen which is adapted to pass light corresponding to at least two other spectral regions and is carried on the rear surface of the supporting means, and an emulsion which is superimposed on the multi-colored screen and is adapted to record light passed by the screen.

2. For use in the production of colored photographs, the combination of a transparent supporting means, an emulsion layer which is adapted to record light from the blue region of the spectrum only and is carried

by that surface of the supporting means which will face the lens, a second emulsion layer which is adapted to record light from at least two other spectral regions and is carried by the rear surface of the supporting means, and sandwiched between the two emulsion layers and carried by the supporting means a multi-color screen adapted to pass light corresponding to the spectral regions to be recorded by the rear emulsion layer.

3. For the production of three-color photographs by the simultaneous exposure of two sensitized surfaces placed one behind the other with respect to the camera lens, the combination of a transparent supporting means, a blue-sensitive emulsion carried on that surface of the supporting means which will face the lens, a panchromatic emulsion carried on the rear surface of the supporting means, and sandwiched between the two emulsion layers and carried on the supporting means a two-color screen comprising juxtaposed red and green elements.

4. For use in the production of colored photographs by the simultaneous exposure of two sensitized surfaces placed one behind the other with respect to the camera lens, the combination of a composite transparent support comprising a front layer and a back layer which are superimposed but separable from one another, a blue sensitive emulsion carried on the outermost surface of the front layer of the support, a two-color screen comprising juxtaposed red and green elements carried on the outermost surface of the rear layer of the support, and superimposed on the two-color screen an emulsion which is sensitive to the light transmitted by the screen.

5. For use in the production of colored photographs the combination of a single transparent support, an emulsion which is adapted to record light from the blue region of the spectrum and is carried by that surface of the support which will face the lens in such manner that it can be readily stripped from the support after development, a multi-color screen which is adapted to pass light corresponding to at least two other spectral regions and is carried by the rear surface of the support, and an emulsion which is superimposed on the multi-colored screen and is adapted to record light passed by the screen.

6. For the production of colored photographs by the simultaneous exposure of two sensitized surfaces placed one behind the other with respect to the camera lens, the combination of a single transparent support, an emulsion layer which is adapted to record light from the blue region of the spectrum, is carried by that surface of the support which will face the lens, and is adapted to be stripped from the support after development, a second emulsion layer which is adapted to record light from at least two other spectral

regions and is carried by the rear surface of the support, and sandwiched between the two emulsion layers and on the support a multi-color screen adapted to pass light corresponding to the spectral regions to be recorded by the rear emulsion layer.

7. For use in the production of colored photographs, the combination with an emulsion adapted to record light from the blue region of the spectrum and to face the lens, of a multicolor screen which is adapted to pass light corresponding to at least two other spectral regions located at the rear of the said emulsion, an emulsion located at the rear of said screen and adapted to record light passed by the screen, and means for supporting said emulsions and screen.

In testimony whereof I affix my signature.
GEORGE SYDNEY WHITFIELD.
